UNITED STATES PATENT OFFICE.

WALTER H. HOFMANN, OF NEW YORK, N. Y.

MOLDING-MACHINE.

No. 918,551.

Specification of Letters Patent. Patented April 20, 1909.

Application filed December 10, 1907. Serial No. 408,731.

To all whom it may concern:

Be it known that I, WALTER H. HOFMANN, a citizen of the United States, and whose residence and post-office address is Richmond 5 Hill, borough of Queens, county of Queens, city and State of New York, have invented a certain new and useful Molding-Machine, of which the following is a full, clear, and exact description.

10 This invention relates to the molding of sand in foundries.

The principal objects of the invention are to provide a device for this purpose in which the sand shall be packed or compressed in 15 such a manner that it will be tucked in around the pattern on all sides thereof, this being accomplished by an improved means for securing a progressive compression of the sand, preferably first lengthwise of the flask 20 in one direction and then back along the flask in the other direction; also to provide efficient mechanism for accomplishing this result in a simple manner by the use of a heavy cylindrical roller, the body portion of 25 which is smooth-surfaced and uniform from end to end for compressing the sand by its own weight and supported entirely by the flask while compressing it.

The invention also comprises improved 30 means for operating the roller and adjustable means located outside the flask for supporting the roller independently of the flask when not in operation, whereby the roller can be brought substantially to the level of the top 35 thereof; also means adapted to be located in the flask for preventing the sand from being packed too hard over the projecting portions of the pattern; and generally to improve and 40 simplify the construction of sand ramming or packing devices.

Further objects and advantages of the invention will appear hereinafter.

Reference is to be had to the accompanying drawing, in which—

45 Figure 1 is a side elevation of a machine embodying this invention; Fig. 2 is a transverse sectional view of the same showing a preliminary operation without the roller; Fig. 3 is a view similar to Fig. 2, showing the 50 parts in the position occupied while the sand is being packed; and Fig. 4 is a similar view showing the pattern withdrawn, the roller being located at the end of the flask.

55 Although several devices have been suggested in which rollers are to be employed for packing the sand, or for other purposes, it

has heretofore been the general practice in ramming sand around patterns for the production of castings to employ either hand- 60 rammers or vertically moving rammers operated by pneumatic, hydraulic or electric motive power. In the use of these devices it has been found that the "pick rammer" which has a comparatively small pressing or ramming surface, tends to create spots of various compressed consistencies and when the 65 "butt rammer" which has a greater pressing or ramming surface is substantially used upon sand which has been pick rammed, the consistency of the whole mass of sand surrounding the pattern is uneven and not calculated to procure the best results when the molten metal is flowed into the mold.

In the use of the various vertically operated power rammers, the sand frequently 70 fails to fill the crevices and interstices of the pattern, when such exist, and through such failure, imperfect molds are often obtained, and many castings have to be thrown away 75 in daily foundry practice. In both cases 80 also, it is of course necessary to exercise extreme care to secure good results, so that all methods of ramming which are in common use involve the employment of skilled labor which is relatively highly paid, and is a very 85 slow process, while the power rammers are more imperfect in results and a power plant of some kind is required for their operation.

This invention is designed for the purpose 90 of greatly reducing the cost of labor both by rendering it possible to use unskilled labor and by reducing the time required for ramming up the molds, and at the same time to provide a machine which while capable of 95 being operated by power will not require an extensive power plant, and can be run advantageously without a mechanical power plant at all.

Referring now to the drawings it will be seen that an ordinary well-known type of 100 flask-supporting and pattern-operating molding machine is illustrated involving a frame A on which a reciprocable pattern B is mounted, adapted to be operated through a stripping plate M or in any other desired 105 manner and to be held rigidly in position while the sand is packed by means of levers connected with an operating handle J. On the bottom board or stripping plate M on the machine is rigidly supported the flask C 110 which may be of any ordinary construction, but is shown as comparatively long and nar-

row, because this invention while capable of general use is somewhat more advantageous when used for flasks of this general shape. In the drawings the flask is shown as stationary. The sand D is placed in the flask and does not ordinarily need to be stricken off, although this may be done if desired. If there is a projecting part on the pattern, a bar L is placed in the sand above the pattern before the molding operation is commenced, as shown in Fig. 2. This is then removed to leave a groove or depression in the sand above the projecting part of the pattern, so that as the sand is uniformly compressed in the flask there will not be a hard spot in contact with the said projecting portion. Whether this is done or not the next step in the operation of the device is to pass over the surface of the sand a heavy cylindrical smooth-surfaced roller E adapted to compress the sand entirely by its own weight. This roller rests on the edges of the flask and is supported entirely thereby while compressing the sand, except that on its first passage over the flask it may be supported indirectly by the sand in the flask. It is provided with flanges F located outside the edges of the flask for the purpose of keeping it in proper position.

30 The method of operation is as follows:— First the roller is passed once over the flask from one end to the other to form a preliminary compression and to progressively compress the sand against the pattern from one side. This operation is very complete as the roller compresses the sand uniformly from one side of the flask to the other, and also by its progressive movement secures uniform compression from one end to the other. If 35 the sand is heaped up very much on the flask before the roller passes over it, as is indicated in Fig. 1, the roller may not rest directly on the edges of the flask during its first passage over, but after this is completed it is drawn back and then it rests directly on the edges of the flask and compresses the sand down to a level with them. It will be seen that if on the first passage of the roller it compresses the sand on the near side of the pattern a little 40 more firmly than on the far side, or if it has any tendency to push the sand away from the far side this will be entirely corrected on the reverse motion of the roller, so that a thorough, complete, and uniform compression is secured as has been amply demonstrated in practice. The roller may be operated in any desired way, but a means is shown extending substantially at right angles to the axis of the roller, and moving horizontally back and 45 forth, consisting of a rack G operated by a pinion H which may be turned by power or by hand as desired. When the roller is drawn away from the flask, it is carried on tracks O located outside the flask substantially on a level with the top thereof and

preferably pivoted to a stationary support P adapted to be held up by a framework of any desired character, and its forward end is adjustably supported as for example, by means of blocks I. The adjustment of the forward end may be secured in any desired way, but when supported by the blocks it is secured simply by removing and replacing them until the track is brought to the level of the top of the flask.

75 It will be understood, of course, that while certain forms of patterns and flasks have been shown, the invention is not limited to any particular form but it has been found to be particularly applicable to the molding of 80 columns, pipes, and other long articles. It will be seen also that the flask may be supported in any desired manner, but it is shown here as supported in stationary position, the molding machine itself constituting means 85 for rigidly supporting it. The pattern also is shown as rigidly supported in the flask during the molding operation by the link motion connected with the handle J. It will be seen also that the heavy roller which 90 compresses the sand by its own weight forces the sand particles compactly into every crevice or opening in the pattern, thereby securing a mold which is more nearly perfect than has been secured by any of the ordinary 95 methods heretofore employed, so that a casting can be made that will be substantially free from roughness or scabs. The sand particles under the progressive rolling pressure of the roller are forced one over another into 100 the smallest depressions in the pattern.

105 While I have illustrated and described a certain form in which the invention has practically been carried out, I am aware that many modifications may be made therein by any person skilled in the art without departing from the scope of the invention as expressed in the claims. Therefore I do not wish to be limited to all the features of construction herein shown, but

110 What I do claim is:—

1. In a foundry molding apparatus, the combination of a flask, means for rigidly supporting a pattern in the bottom of the flask, means for withdrawing the pattern from the 115 flask, and a sand ramming device comprising a heavy cylindrical smooth-surfaced roller uniform from one edge of the flask to the other, the uniform portion thereof being of greater width than the interior width of the 120 flask and adapted to roll over the flask to compress the sand on the pattern by its own weight and supported entirely by the top edges of the flask while compressing the sand.

2. In a foundry molding machine, the 125 combination of a rigidly supported flask having sides and ends of the same height, a pattern support at the bottom thereof, said flask and pattern support being separable from each other, and a ramming device for the 130

mold comprising a cylindrical roller of uniform diameter throughout its central portion, the uniform portion of the roller projecting over the edges of the flask, and resting substantially in contact with the tops of said edges whereby said roller can roll over the whole length of the flask and over the ends thereof without being lifted.

3. In a sand molding apparatus, the combination of a flask, and a roller adapted to roll over the flask to compress the sand therein to a level surface and supported substantially in contact with the edges of the flask while compressing the sand, and means located outside the flask substantially on a level with the top of the flask for supporting said roller independently of the flask, when the roller is not in position for compressing the sand in the flask.
- 20 4. In a sand molding apparatus, the combination of a flask, and a heavy smooth-surfaced roller adapted to roll over the flask to compress the sand entirely by its own weight and supported on the edges of the flask while compressing the sand, and vertically adjust-

able means located at one end of the flask and on a level with the top of the flask for supporting the roller, when the roller is not in position for compressing the sand in the flask.

30 5. In a sand molding apparatus, the combination of a flask, a heavy smooth-surfaced roller adapted to roll over the flask to compress the sand entirely by its own weight and supported on the edges of the flask while compressing the sand, and means adapted to be placed on the sand in the flask and over which said roller rolls for producing a groove or depression in the molding sand.

35 6. In a sand molding apparatus, the combination of a flask, a heavy smooth-surfaced roller adapted to roll over the flask to compress the sand, and means adapted to be placed on the sand in the flask and over which said roller rolls for producing a groove or depression in the molding sand.
